APPARATUS FOR DEFINING CHARACTERS ON IMPRESSION-RECEIVING MATERIAL

Donald Rudolf Lambert, Carshalton, England, assignor to Powers-Samas Accounting Machines Limited, London, England, a British company

Application February 16, 1954, Serial No. 410,656

Claims priority, application Great Britain March 18, 1953

9 Claims. (Cl. 101—93)

This invention relates to an improved apparatus for defining characters on impression-receiving material.

It is a main object of the invention to provide apparatus for automatically effecting the definition of characters on impression-receiving material, e. g. paper, at a relatively high speed and in carrying the invention into effect one or more styluses is or are employed, each stylus being capable of defining any one of a predetermined number of characters. By a "relatively high speed" is to be understood the capacity of a stylus or of each stylus to define characters at a rate of 150 or more characters per minute.

According to the invention there is provided for defining characters on impression-receiving material, e. g. paper, apparatus comprising a platen, at least one stylus the marking end of which is supported for movement lengthwise towards and away from the platen, stylus reciprocating means operable simultaneously to move the marking end of the stylus in two paths normal one to the other thereby to determine the maximum height and maximum width of a character, and actuating means operable during said simultaneous movement of the marking end of the stylus to apply discrete impulses to the stylus to effect lengthwise movements thereof to cause its marking end to make character-defining marks on impression-receiving material disposed between the platen and the marking end of the stylus.

In order that the invention may be clearly understood one embodiment thereof will now be described, by way of example, with reference to the accompanying diagrammatic drawings in which:

Fig. 1 pictorially illustrates one form of apparatus for defining characters in accordance with the invention.

Fig. 2 is an elevation partly in section and illustrates means for effecting lengthwise movements of styluses.

Fig. 3 is a pictorial view, on line III—III, Fig. 1, illustrating the manner in which a character is defined in accordance with the invention.

Fig. 4 illustrates a character disc for the letter "A," and

Fig. 5 graphically illustrates the manner in which, under control of the disc shown in Fig. 4, a stylus defines the letter "A" on impression receiving material.

Referring to the drawings, the apparatus diagrammatically illustrated therein embodies a plurality of styluses each of which consists of a flexible wire 1, the wire 1 being the inner wire of a flexible cable which cable consists of the inner wire 1 and a flexible outer member 2 which outer member is a fixed member having its opposite ends clamped as indicated in Figs. 1 and 2. The inner wire 1 is movable lengthwise relative to the outer member 2 and extends therethrough to project beyond the opposite ends thereof so the end 3, Fig. 3, thereof is the marking end while the opposite end 4, Fig. 2, of the wire is an impulse-receiving end which co-operates with the armature 5 of a moving coil solenoid 6 for movement lengthwise thereby.

The marking ends 3 of the flexible wires 1 are supported in side by side relation by the outer members 2 and are directed towards a platen 7, Figs. 2 and 3, over which, in any suitable known manner, there is fed a web 8 of im-

2

pression-receiving material, such as paper, the feeding apparatus for which, as is customary, is arranged to feed the paper to successive line positions thereof, the paper being stationary during character-defining operations.

5 Also over the platen 7 is fed a web 9 of transfer media such as a carbon ribbon or the like.

The marking ends 3 of the wires are supported by a first reciprocating guide element 10 and a second reciprocating guide element 11, the wires passing through apertures 12 in the guide element 11 to be engaged thereby.

10 The first guide element 10 is adjacent to the opposite ends thereof, provided with V-grooves each of which embraces a post 13, Fig. 1, so that the guide element 10 is slidable lengthwise of the posts. A pin 14 extends from each 15 end of the first guide element 10 and is engaged in a slot 15 formed in a bell-crank lever 16 supported on a pivot 17. The bell-crank lever 16 carries a cam follower 18 which is urged towards a cam 19 by a spring 20. The cam 19 is rotatable with a shaft 21 which is continuously rotated 20 in any suitable manner from the main drive of the machine, not shown.

The second guide element 11 has a tongue 22 extending lengthwise thereof, the tongue being housed in a groove extending lengthwise of the first guide element 10 so that 25 the second guide element 11 is carried by the first guide element 10 and is supported for sliding movement lengthwise thereof and in a direction normal to the direction of movement of the first guide 10, as indicated by the double-headed arrows 23 and 24, Figs. 1 and 3. To

30 one end of the second guide element 11 is connected an eccentric strap 25, Fig. 1, the strap 25 co-operating with an eccentric 26 rotated by a shaft 27, also continuously rotatable by any suitable means, not shown, from the main drive of the machine. The shafts 21 and 27 are

35 rotated simultaneously and in timed relation in order that the movements of guide elements 10 and 11 in directions 23, 24 are effected simultaneously so that the guide elements move the marking ends 3 of the styluses 1 simultaneously in two paths, normal one to the other, as determined by the cam 19 and eccentric 26 so that 40 the marking ends 3 of the styluses each trace out relative to the stationary web 8 a path as indicated by the sloping lines 24a, Fig. 5. The arrangement is such that the reciprocating movements 23 of the first guide element 10

45 determine the maximum height of a character to be defined by a stylus 1 while the reciprocating movements 24 of the second guide element 11 determine the maximum width of the character.

50 The cam 19 and eccentric 26 are so timed that while the cam 19 is causing the guide element 10 to make a single traverse in one direction the eccentric 26 causes the guide element 11 to make a plurality of reciprocations 24, the extent of movement of element 11 being indicated as

55

24
2

in Fig. 5. In the embodiment of the apparatus herein described it is assumed that while the guide element 10 makes one reciprocation 23 the guide element 11 makes 60 eleven reciprocations 24. However, as can be seen from Fig. 5, the arrangement is such that discrete impulses are applied to the wires 1 only during the first eight of a cycle of eleven reciprocations 24, the remaining three reciprocations of the cycle being idle and representing 65 the interval during which selection is made from a plurality of continuously rotating character discs, of which one 28 is illustrated in Fig. 4, to control the operation of solenoids 6. It will be understood that the ratio of 1:11 is given by way of example only and that other ratios can be employed to suit the nature of the work 70 to be done.

As viewed in the drawings, the guide element 10 is making its downward stroke during character definition and at the end of its downward stroke which is a steady movement

23
—
2

from top to bottom, as viewed in Fig. 5, the roller 18 drops from the peak of the cam down a step 29 formed thereon so that the return movement is a very quick movement. The quick return movement of guide element 10 is necessitated by the fact that it must be completed during the line-feeding operation of paper 8.

Each character disc 28 is electrically connected with each solenoid 6 and is provided with peripheral electrical contacts 28a . . . 28cc for co-operation with brushes, not shown, so that at intervals and for periods determined by the contacts the solenoid 6 is energised and imparts discrete impulses to the impulse-receiving end 4 of wire 1 causing the wire to be moved lengthwise to impinge against the transfer media 9 so that, according to the length of a contact, a dot or a line is marked on the paper web 8. In Figs. 4 and 5 the reference numerals 28a . . . 28cc indicate the contacts and the dots or lines marked as a result thereof, the contact 28p resulting in the marking of a line.

Although in the example given character-determining discs have been described as controlling the operation of solenoids 6 the manner of selection of the discs 28 for operation thereof forms no part of the present invention and is not illustrated in the drawings, it being understood that the electrical pulses to control operation of the solenoids 6 can, if desired, be obtained from sources other than discs 28.

On application of an electrical pulse to a solenoid 6, the armature 5 thereof, as mentioned above, effects lengthwise movement of the inner wire 1 so that the wire is impinged against the transfer media 9 and paper 8. It will be understood that the extent of lengthwise movement of the wire 1 is very short and after an impulse has been applied thereto the arrangement is such that the wire 30, Fig. 2, which connects the moving coil of the solenoid to terminals, not shown, act in conjunction with the tendency for wire 1 to straighten and the reactionary pressure exerted thereon by the impression-receiving material, which is under tension, to restore the wire 1 and armature 5 to the starting positions thereof.

It will be understood that, if desired, a single stylus 1 may be employed to effect the definition of characters on impression receiving material such as tape, but in the preferred embodiment of the invention the apparatus comprises a plurality of wires 1, as illustrated in Figs. 1 and 3, the apparatus being used in conjunction with a statistical machine controlled by records such as perforated record cards, or perforated tape, or by cards, tape or other data-bearing media on which data is recorded by marks, for example marks having magnetic properties or light-absorbing properties, and from which the data is sensed to control the operations of the machine.

One form of statistical machine to which the apparatus may be applied is a tabulating machine, in which instance a stylus 1 may be controlled either directly as a result of the sensing of data from a record, or by a reading-out operation from an accumulator incorporated in the machine. The apparatus may, at some times, be controlled by records, and at other times by a reading-out operation from the accumulator.

Another form of statistical machine to which the apparatus can be applied is that form of statistical machine, known to the art as an interpreter, in which data sensed from a record is visually defined either on the record from which the data is sensed or on another record fed through the machine either in precedence to or succeeding the record from which the data is sensed.

In the embodiment of the invention described above,

the styluses have been described as flexible wires, but it will be understood that, if desired, a stylus can have a form other than that of a wire and may comprise a stylus which is provided with marking material so that it makes an impression by direct contact with the impression-receiving material, thus avoiding the necessity of the transfer media 9 mentioned above. Thus the stylus may comprise a form of ball-point pen or it may be an element provided with a thin wick to which marking fluid is fed to effect the character-defining marks on the paper.

From the foregoing it will also be understood that during the definition of a character the paper 8 is stationary, the paper being fed as is customary to the individual line printing positions thereof between the printing of successive characters by the individual styluses, and that, if desired, imprinting may be effected on sheets instead of on a web as hereinbefore described.

I claim:

1. For defining characters on impression-receiving material, e. g. paper, apparatus comprising a platen, at least one stylus supported for movement lengthwise towards and away from the platen, a first stylus reciprocating element supported for reciprocation in a path determining one maximum dimension of a character, a second stylus reciprocating element co-acting with the marking end of the stylus and movable with said first element and relative thereto in a path normal to the path of said first element to determine the other maximum dimension of a character, a first operating means operatively coupled to said first element to effect reciprocation thereof, a second operating means operatively coupled with said second element and actuated in timed relation with said first operating means to effect a predetermined number of reciprocations of the second element for each reciprocation of the first element, and actuating means operable during movement of said first element in one direction of movement thereof to apply discrete impulses to the stylus to effect lengthwise movements thereof to cause its marking end to make character-defining marks on impression-receiving material disposed between the platen and the marking end of the stylus.

2. For defining characters on impression-receiving material, e. g. paper, apparatus comprising a platen, a plurality of styluses supported in side-by-side relation for independent movement lengthwise towards and away from the platen, a first guide element supported for reciprocation in a path determining the height of characters definable by said styluses, a second guide element engaging the marking end of each of the styluses and supported by the first guide element for movement therewith and for reciprocation relative thereto in a path normal to the path in which the first guide element is reciprocable thereby to determine the maximum width of characters definable by the styluses, a first operating means operatively coupled to said first element to effect reciprocation thereof, a second operating means operatively coupled with said second element and actuated in timed relation with said first operating means to effect a predetermined number of reciprocations of the second element for each reciprocation of the first element, and actuating means operable during movement of said first guide element in one direction of movement thereof to apply discrete impulses to a stylus to effect lengthwise movements thereof to cause its marking end to make character-defining marks on impression-receiving material disposed between the platen and the marking ends of the styluses.

3. Apparatus according to claim 2, wherein the first operating means includes a pivoted cam-follower operatively connected with the first guide element, a cam co-operating with the cam-follower, a first continuously rotatable shaft supporting said cam for rotation therewith, and the second operating means includes an eccentric strap operatively connected with the second guide element, an eccentric co-operating with said strap, and a second shaft continuously rotatable in timed relation with

said first shaft and supporting the eccentric for rotation therewith.

4. Apparatus according to claim 3, wherein the actuating means for each stylus comprises a moving coil solenoid including a movable armature to apply said discrete impulses to the stylus.

5. Apparatus according to claim 3, wherein the first guide element is supported for reciprocation by said cam-follower and guide posts co-operation with V-grooves formed in the first guide element adjacent the opposite ends thereof.

6. For defining characters on impression-receiving material, e. g. paper, apparatus comprising a platen, a plurality of flexible wires each consisting of a flexible outer member supported by the opposite ends thereof and an inner wire extending therethrough to project beyond the opposite ends thereof and form a stylus having a marking end and an impulse receiving end, the inner wires being supported by their outer members in side-by-side relation for movement lengthwise towards and away from the platen, a first guide element supported for reciprocation in a path determining the height of characters definable by said inner wires, a second guide element engaging the marking end of each of the inner wires and supported by the first guide element for movement therewith and for reciprocation relative thereto in a path normal to the path in which the first guide element is reciprocable thereby to determine the maximum width of characters definable by the inner wires, a first operating means operatively coupled with said first element to effect reciprocation thereof, a second operating means operatively coupled with said second element and actuated in timed relation with said first operating means to effect a predetermined number of reciprocations of the second element for each reciprocation of the first element, and actuating means operable during movement of said first guide element in one direction of movement thereof to apply discrete impulses to the impulse receiving end of an inner wire to effect lengthwise movement of the wire to cause the

marking end thereof to make character-defining marks on impression-receiving material disposed between the platen and the marking ends of the wires.

7. Apparatus according to claim 6, wherein the first operating means includes a pivoted cam-follower operatively connected with the first guide element, a cam co-operating with the cam-follower, a first continuously rotatable shaft supporting said cam for rotation therewith, and the second operating means includes an eccentric strap operatively connected with the second guide element, an eccentric co-operating with said strap, and a second shaft continuously rotatable in timed relation with said first shaft and supporting the eccentric for rotation therewith.

8. Apparatus according to claim 7, wherein the actuating means for each said inner wire comprises a moving coil solenoid including a movable armature for co-operation with the impulse-receiving end of the wire thereby to impart said discrete impulses to the wire to effect lengthwise movement thereof towards the platen.

9. Apparatus according to claim 8, wherein the first guide element is supported for reciprocation by said cam-follower and guide posts co-operating with V-grooves formed in the first guide element adjacent the opposite ends thereof.
